UNITED STATES PATENT OFFICE.

FRANK W. DREWS, OF WILLMAR, MINNESOTA.

WRENCH.

1,311,801.

Specification of Letters Patent. Patented July 29, 1919.

Application filed April 22, 1919. Serial No. 291,812.

To all whom it may concern:

Be it known that I, FRANK W. DREWS, a citizen of the United States, residing at Willmar, in the county of Kandiyohi and 5 State of Minnesota, have invented new and useful Improvements in Wrenches, of which the following is a specification.

This invention relates to wrenches and comprehends a construction wherein the 10 movable jaw can be very quickly and easily adjusted with regard to the fixed jaw, and effectively held in gripping relation therewith.

To this end the invention consists in the 15 provision of a wrench having a toothed shank, upon which a movable jaw is slidably mounted, a toothed locking element being slidably associated with the movable jaw and connected with a cam which actuates to 20 release the element from engagement with the shank, but effectively holds the teeth of said locking element engaged with the teeth of the shank.

The nature and advantages of the invention 25 will be better understood when the following detailed description is read in connection with the accompanying drawings, the invention residing in the construction, combination and arrangement of parts as 30 claimed.

In the drawing forming part of this specification, like numerals of reference indicate similar parts in the several views and wherein:

35 Figure 1 is a perspective view of the wrench constructed in accordance with my invention.

Fig. 2 is a sectional view taken on line 2—2 of Fig. 1.

40 Fig. 3 is a detail view of the movable jaw.

Fig. 4 is a similar view of the associated cam and locking element.

45 Fig. 5 is a perspective view of the movable jaw showing a modified form of the invention.

Referring to the drawings in detail, 10 indicates the shank of the wrench which is substantially rectangular in formation for the major portion of its length, and cylindrical for the remaining portion of its length 50 to accommodate a handle 11. A fixed jaw 12 is arranged at one end of the shank, while one of the longitudinal edges of the shank is provided with teeth 13.

55 A movable jaw 14 is mounted upon the shank 10 for free sliding movement toward

and away from the fixed jaw 13. The movable jaw 14 is provided with a pocket 15 in which is arranged the locking element or block 16, susceptible of movement toward 60 and away from the shank 10. One side of the locking element or block is provided with teeth 17, which are adapted to co-operate with the teeth of the shank to hold the movable jaw in gripping relation with regard to the fixed jaw, as will hereinafter be more fully described. A cam 19 having 65 spaced apertured lugs 20 is positioned between the sides of the movable jaw, immediately above the locking element or block, a 70 pivot 21 being passed through the sides of the movable jaw and the lugs 20 of the cam for supporting the latter for pivotal movement. Links 22 provide a connection between the locking element or block and the 75 cam 19 so that movement of the cam controls the movement of the locking element or block. As shown in Fig. 1, a manipulating element 23 is secured to the cam projecting therefrom in a plane parallel with the shank 80 10, the manipulating element extending an appreciable distance beyond one side of the movable jaw to be readily grasped by the user of the wrench.

In practice, when it is desired to effect an 85 adjustment of the movable jaw with regard to the fixed jaw, the manipulating element 23 is actuated to move the cam 19 upon its pivot in an upward direction, during which movement of the cam the latter is gradually 90 moved away from the locking element or block, but by reason of the connection between the cam and the block by means of the link 22, the locking element or block is moved away from the shank 10. The movable jaw is thus released for free sliding movement, and can be readily and easily positioned at any desired location upon the shank 10. Subsequent to the positioning of the movable jaw with regard to the fixed 100 jaw, the manipulating element 23 is actuated to swing the cam in a reverse direction, during which operation the cam engages the locking element or block moving the latter into engagement with the shank 10 and 105 holding the teeth of the block effectively engaged with the teeth of the shank. Manifestly, when the parts are thus positioned the movable jaw is securely and positively held in gripping relation with regard to the 110 fixed jaw.

Upon reference to Fig. 5 of the drawing,

it will be noted that the manipulating element 25 for the cam 26 is disposed to operate at one side of the wrench. The cam 26 controls the movement of the locking element 27 exactly the same in this instance as hereinabove described in connection with the preferred form of the invention, the difference in construction residing in the provision of a slot 28 in the movable jaw for the reception of the manipulation element 25 when the cam has been moved to an active position to hold the movable jaw locked upon the shank. When the manipulating element is so disposed, it lies flush with one side of the movable jaw, thus eliminating any projection which casually might be brought into contact with some obstacle during the use of the wrench, and effect the release of the jaw.

20 I desire to have it understood that I do not limit myself to the exact construction and arrangement of parts herein disclosed, and that such changes may be resorted to when desired as fall within the scope of what is claimed.

25

Copies of this patent may be obtained for five cents each, by addressing the "Commissioner of Patents, Washington, D. C."

What I claim is:—

A wrench comprising a shank having a toothed surface, a fixed jaw, a movable jaw slidably mounted on the shank and provided with a pocket, a locking element movably arranged within said pocket and having teeth to coöperate with the teeth of the shank to hold said jaw in a given position on the shank, a lever extended transversely of the sliding jaw, and pivoted between the walls of said pocket, a cam forming an integral part of said lever and offset therefrom at one end, said cam being arranged within said pocket and operable therein, a pair of links freely pivoted at corresponding extremities to the opposite end portions of said cam, the opposite ends of said links being freely pivoted to the adjacent ends of said locking element, whereby the latter is lifted and lowered toward and away from the shank in said pocket when the lever is swung upon its pivot in reverse direction.

40 In testimony whereof I affix my signature.

FRANK W. DREWS.
